UNITED STATES PATENT OFFICE.

CHARLES W. THOMPSON, OF QUINCY, MASSACHUSETTS, ASSIGNOR TO HARVEY C. WHEELER, OF BOSTON, MASSACHUSETTS.

TOWEL HOLDER AND FILLER FOR SAME.

Application filed March 14, 1927. Serial No. 175,137.

One of the objects of my invention is to provide a simple and inexpensive mechanism for a towel cabinet wherein a quantity of clean towels is stored, so that the individual towels may be readily removed, used and dropped into another part of the cabinet where they are automatically stored in orderly fashion, and another clean towel automatically present itself ready for use, 10 and so on until all of the clean towels are used.

Another object of my invention is to provide a compact bunch of towels formed by permanently attaching a number of 15 lengths of toweling closely together to a fabric backing sheet. This bunch is put into the cabinet as a unit, the towels individually used and stored therein while still remaining attached to the backing sheet, 20 and when all have been used, withdrawn and laundered and dried as a unit. I have found that when such a bunch of towels is washed and dried the towels come out smooth and unwrinkled, and do not require 25 any mangling or ironing. This eliminates the cost of expensive mangling machinery, also the towels cannot be used for shining shoes, as dust cloths, etc., nor can individual towels be stolen or lost. It will, therefore, be seen that my towel bunch saves 30 space because of its compactness; saves money, labor and time since the towels need not be ironed, and prevents loss and misuse because the towels are irremovably attached 35 to one backing sheet.

In the drawings forming part of this specification, Fig. 1 is a perspective view, on a small scale of a filler for a towel supply device consisting of a bunch of towels 40 united in accordance with my preferred method. Fig. 2 illustrates another way by which to unite the towels. Fig. 3 shows another arrangement thereof. Fig. 4 is a side sectional view of the preferred form of 45 cabinet for the reception and delivery of the towels showing the clean towels in position for withdrawal individually and the used towels properly stored. Fig. 5 is a sectional view on a small scale of another 50 form of holder for the towels. Fig. 6 is a perspective view of still another form.

In the preferred form of my towel grouping illustrated in Fig. 1, the towels 1 are each doubled and stitched along the fold 55 to a strip of strong fabric 2, which I term

a carrier, whereby each length of toweling makes two towels. A multiplicity of these lengths are located closely together to form the towel filler. The other methods illustrated for thus disposing the towels are 60 shown in Figs. 2 and 3; that of Fig. 2 consisting in forming an eye at each of two corners, and running a cord 4 through all the holes or eyes at adjacent corners, these cords attaching the towels to fabric flaps 65 5, 6. The method shown in Fig. 3 consists in securing to the strip 2 a large number of transversely disposed metallic dovetail members 7, into which may be drawn the edges of the towels 9 having a cord 10 70 stitched therein.

Among other ways of utilizing these bunches of towels, an end of the fabric 2 may be fastened upon a shelf 11, as indicated in Fig. 5, each towel being doubled. 75 As each towel is drawn forward and used, it can then be permitted to drop and hang down from the remainder.

Another method consists in attaching the bunch of towels to an endless apron 13 80 mounted on rollers 14 each supported at one end only to permit the easy removal of the apron and its contents. At one side of the apron is a fixed shelf 15 downwardly inclined toward the apron but spaced therefrom. The free edge of the lowermost towel being seized and drawn down therefrom, it also can be dropped after using. See Fig. 6. As each towel is withdrawn, it should be pulled downward sufficiently to 85 cause the endless apron 13 to carry the pendent used towels up into the cabinet compartment 16 to a limited extent. 90

My preferred construction of cabinet, that shown in Fig. 4, consists of sides 20, back 95 21, top 22, bottom 23, a shelf 24 dividing the interior into two chambers 25, 26, the upper chamber being about half the height of the lower. Between the sides 20 and the adjacent edges of the shelf 24 a space is left for the free passage of arms 30 pivotally supported at 31, and terminally united by a cross bar 32; said arms being preferably made by suitably bending a single length of iron rod into an approximate U-shape. 100 This cross bar passes freely through slots 33 in fins 33^a formed on each side of a vertical partition 34; and the lower end of each arm 30 is connected with a tension spring 35 by means of which the partition 105 110

34 is resiliently pressed toward a swinging door 36 normally locked by means of latches 37.

In the partition 34 is a slot 39 having its edges forced forward sufficiently to permit the button 40 attached to the carrier fabric 2, to retain the towels 1 in place on the shelf 24. At the other end of the carrier is an eye 41 adapted to be caught on the hook 42 rising from the cross bar 43 which unites arms 44 pivotally supported at 31 and provided with tension springs 45 for drawing them inward.

In filling the cabinet, the door 36 is unlatched and swung up out of the way. The towels 1, each having been given a single fold at approximately midlength so that their free ends are forward and near the carrier 2, are attached to the partition 34 by inserting the button 40 in the slot 39, and then pushed inwardly causing the partition to move backwardly until the door 36 can be latched. The hook 42 is then caught in the eye 41.

To use a towel, the free end of the foremost one is grasped and drawn outwardly and downwardly until the towel is wholly exposed. After using, it is dropped into the lower chamber 26. As each towel is drawn out, the partition 34 presses the remainder forward under the urging of the springs 35, and the arms 44 draw the used towels inwardly under the urging of springs 45.

When all of the towels have been used, the ends of the carrier 2 are disconnected from the partition 34 and hook 42, the bunch is removed, washed and dried as a whole.

What I claim as my invention is:

1. A filler for a towel supply device which comprises a washable backing sheet or carrier of flexible material having provision for attachment to the actuating means of a towel supply device, a multiplicity of sheets of towel material stitched along closely adjacent, parallel lines, respectively, to secure said sheets to said washable backing sheet.

2. A filler for a towel supply device which comprises a towel backing sheet or carrier having means whereby it may be fastened to a towel supply device, a multiplicity of sheets of towel material inseparably attached to said carrier, said towel sheets being folded upon themselves so that their free ends are adjacent to said carrier.

3. A filler for a towel supply device, which comprises a flexible carrier, a multiplicity of sheets of towel material having lines of permanent attachment to said carrier, said lines of attachment being so closely related as to provide a bunch of towels, and the free ends of the towels being turned inwardly to provide folds.

65 4. A filler for a towel supply device,

which comprises a flexible carrier, a multiplicity of sheets of towel material having lines of permanent attachment to said carrier, said lines of attachment being so closely related as to provide a bunch of towels, and the free ends of the towels being turned inwardly to provide folds, said flexible carrier being provided with end extensions beyond said bunch, which end extensions have provision for attachment to the actuating means of a towel supply device. 70

5. A holder for a carrier having a bunch of towels attached thereto side by side, which carrier has provision for attachment to the actuating means of the holder, comprising a supporting means for said bunch of towels, a cabinet separated into two chambers by said supporting means, a member adapted to press said bunch of towels forward in one chamber, and means adapted to receive an end of said carrier and to draw said carrier with the used towels into the other chamber, said cabinet having provision whereby a towel may be grasped and withdrawn from it. 80

6. A towel holder for a fabric carrier having an eye at one end and a button at its other end, and a bunch of closely disposed towels attached to said carrier, comprising a supporting means, a cabinet separated into two chambers by said supporting means, a member removably receiving said button and adapted to yieldingly press said bunch forward, and means below said supporting means adapted to be engaged with said eye and to yieldingly draw the latter and the carrier within the lower chamber of said cabinet. 85

7. A holder for a carrier having a bunch of towels attached thereto side by side, comprising a cabinet having an intermediate shelf, a door for the space above but spaced from said shelf, a vertical partition yieldingly pressed along said shelf toward said door, removable means for attaching one end of said carrier to said partition, and yielding means connected with the other end of said carrier drawing it within the cabinet beneath said shelf. 100

8. A holder for a carrier having a bunch of towels attached side by side thereto, comprising a cabinet having an intermediate shelf, and a locking door spaced above and at the front of said shelf, a vertical partition above said shelf, a spring actuated swinging arm adapted for pressing said partition toward said door, and a spring arm adapted to be engaged with an end of said carrier below said shelf and to draw said carrier inward. 110

9. A holder for a carrier having a bunch of towels attached side by side thereto, and having a button at one end, comprising a cabinet having a shelf laterally spaced from the interior of the cabinet, a vertical par- 120

130

tion above said shelf having an open slot adapted to receive said button, a pair of arms having a cross bar uniting their upper ends loosely attached to said partition, the 5 lower ends of said arms being pivoted to the sides of the cabinet, springs for pressing the upper ends of said arms toward said door, and a pair of arms having a cross

bar adapted to be attached to the other end of said carrier, and pivoted at their lower 10 ends to the sides of the cabinet, and springs for drawing the last-named arms inward.

In testimony that I claim the foregoing invention, I have hereunto set my hand this 12th day of March, 1927.

CHARLES W. THOMPSON.
